UNITED STATES PATENT OFFICE.

RAYMOND F. STURGIS, OF RAHWAY, NEW JERSEY, ASSIGNOR TO THE TORRIDION COMPANY, OF NEW YORK, N. Y., A CORPORATION OF DELAWARE.

OIL BURNER.

Application filed February 7, 1925. Serial No. 7,575.

To all whom it may concern:

Be it known that I, RAYMOND F. STURGIS, a citizen of the United States, and a resident of Rahway, county of Union, State of New Jersey, have invented certain new and useful Improvements in Oil Burners, of which the following is a specification.

This invention relates to an oil burner for burning low grade oil with freedom from 10 smoke, noise and accumulation of carbon, and is more particularly adapted to be used in household furnaces where it can be placed directly on the grate of a furnace built to burn coal or other fuel. The invention comprises a symmetrical burner design in which 15 a circular flame is formed so that all parts of the burner at any zone are under uniform temperature conditions. The burner is made of such a nature that it can be made of 20 rugged parts, is easily taken apart and easily adjusted for maximum efficiency.

The invention will be described with particular reference to the accompanying drawings, in which

25 Figure 1 is a vertical section of the burner. Figure 2 is a plan view of a part of the generator.

An open frame 1 adapted to be set on the 30 grate of a furnace or other location has an oil tank portion 2 forming a shallow pan. In the center of this pan an air intake cylindrical portion 3 forms a pipe for a central air draft, the admission of air to which is under control of a damper 4, operatable by 35 handle 5. 6 is an outside conical deflector having a damping portion 7 and a handle 8. This element combines the functions of a damper and deflector for the outside draft. Oil is supplied to the tank 2 by means of 40 oil pipe 9 from a source of oil which may be regulated by a float or by hand valve (not shown) to maintain the oil approximately at the level of the surface of the pan. Overflow of oil, however, is transmitted and will 45 escape into a trough 10 secured to the frame 1, and will flow through pipe 11 back to the source of oil. In the oil tank or pan 2 I arrange a generator or heat conveyer comprising an outer cylinder 12 and inner cylinder 50 13, and a series of copper heat conducting gills 14 fastened between them as shown in Figure 2. The laminations of this generator

are in heat conductive contact with each other and with the inner and outer walls of the heater so as to give a large surface for the transfer of heat from the metal to the oil. The outer rim 12 of this heater has a handle 15 by means of which the heater may be agitated or rotated back and forth to disturb any possible accumulations of carbon. 55 In order to deflect the central draft down onto the oil, I provide a cap 16 which may have internal ribs 17 screw-threaded onto the upper end of the central tube 3. The lower part of the cap is, as shown at 18, 60 formed in a flaring, conical shape in such a manner as to cause the central draft to be first deflected down onto the oil and then escaping over the top of the oil and meeting the draft coming up from under the deflector 6 causes the combined draft, by impinging on the outer surface of the flaring cone 18, to deflect outwardly to give the desired distribution. The cone 18 will, therefore, become hot and serve to maintain the combustion at high efficiency. The permeation of 65 the heat from the flame through the burner will result in the generator 14 increasing the evaporation of the oil so as to produce perfect combustion. The cap 16 may be adjusted by turning it on the thread on pipe 3 so as to raise or lower it and thus control the aperture between the cone 18 and the deflector 6, which will enable the operator to 70 nicely adjust the flame to produce the kind 75 of combustion desired.

I claim:

1. In an oil burner, the combination comprising an oil pan, heat transferring gills in the oil pan in heat conducting relation to the oil and the gases over the pan, a central air inlet passing up through the pan, an air deflector for returning the air passing through the central opening down to and against the central air inlet over the top of the pan and the gills, said air deflector having an upwardly flaring outer surface, and an outside air deflector having conical walls adapted to direct a current of air against the first-mentioned current as it issues from the outer edge of the pan.

2. In an oil burner, the combination comprising an oil pan, heat transferring gills in the oil pan in heat conducting relation to

the oil and the gases over the pan, said gills being carried by a combined rotatable carrier and cleaner for removing carbon, a handle on the carrier for manually rotating the same, a central air inlet passing up through the pan, an air deflector for returning the air passing through the central opening

down to and over the top of the pan, and an outside air deflector having conical walls adapted to direct a current of air against the first-mentioned current as it issues from the outer edge of the pan. 10

RAYMOND F. STURGIS.
